TOOLMAKER'S VISE OR CLAMP

John M. Froblom, Holland, Mich.

Application January 12, 1945, Serial No. 572,518

1 Claim. (Cl. 144—303)

1

This invention relates in general to vises, and in particular to a toolmaker's vise or clamp of the kind adapted for use with a magnetic chuck, or with drilling operations.

One of the objects of the invention is to provide in such a vise simple and rapid means for adjusting the position of one of the jaws, the other jaw being adjusted by screw means.

Another object is to provide in a toolmaker's vise a clear space between the jaws, so that in drilling or like operations there is no possibility of the vise being marred by a tool.

Another object is to provide in a toolmaker's vise a jaw structure which will facilitate the holding of a work piece.

A yet further object is to provide a jaw structure which will insure against slipping of the work piece therein.

Other objects and advantages of the invention will be apparent from a study of the description hereinafter together with the drawings. It is understood, however, that the invention is not limited by the drawings, which merely show a preferred embodiment of the invention, nor otherwise than by the claim subjoined.

In the drawings:

Figure 1 is a plan view of the invention;

Figure 2 is a section taken along the lines 2—2 in Figure 1;

Figure 3 is a view looking in the direction of the arrows 3—3 in Figure 1; and

Figure 4 is a section taken substantially along the lines 4—4 in Figure 1.

Referring particularly to Figure 1 the toolmaker's vise or clamp comprises a crosshead 10 supporting a pair of side members 12, 14, which in turn support jaws 16 and 18. Adjustment of jaw 16 is provided by a screw turning in the crosshead 10. Screw 20 is turned by a slip-crank 22, and is fastened to jaw 16 by means of a screw 24, which is jammed to the bottom of a tapped hole 26 in screw 20.

Means are provided for rapid adjustment of jaw 18, and to this end the side members 12, 14 have on the proximate sides thereof a plurality of slots 28 spaced at regular intervals, any transversely spaced pair of which can be engaged by a swivelable member 30 fastened to the exterior face of jaw 18 by means of nut, bolt and locking washer means, in the manner shown or in any other convenient manner.

To the end that the vise or clamp can hold securely objects having rather large dimensions of breadth and width as compared with depth, and to the end that the work piece to be held

2

in the vise cannot slip downwardly as during a surface grinding operation while the vise and work piece are supported on a magnetic chuck, as shown in Figure 2, and also to the end that the work piece cannot slip out of the vise after the completion of a drilling operation, and as particularly shown in Fig. 4, the proximate faces of the jaws 16 and 18 are provided with work piece supports consisting of ledge surfaces 32 and 34 lying in the same plane and wall surfaces 36 and 38, which have a slight rake, generally about 2°, in such a direction that pressure on the screw will cause the jaws 16 and 18 to exert a downward force, tending to hold the work piece securely.

The vise is also provided with another work piece support 40, 42 on the bottom side thereof, and of smaller dimension than the upper work support for the accommodation of smaller work pieces. It will readily be observed, of course, that the vise may be supported on either side.

The proximate faces of the jaws 16 and 18 are also provided, as shown in Figure 1, with a V-slot for the accommodation of round or square work pieces.

Since working in metals entails the accumulation of waste materials, chips and the like, the upper and lower surfaces of the jaws 16 and 18 are provided with relieved portions 44 which facilitate the placing of the vise on a chuck or other support.

Thus has been described a new and useful improvement in the art of toolmakers' vises or clamps which gives rapid adjustment, large clamping range without the use of a long screw, readiness of adaptation to work pieces of varying sizes and shapes, positive assurance that work pieces will not slip out and clear space between the jaw faces. While the invention has been described in terms of a preferred embodiment, its scope is not to be limited by the terms of said embodiment, nor otherwise than by the terms of the claim here appended.

I claim:

45 In a toolmaker's vise of the class described adapted for holding work pieces, a pair of work holding jaws, a pair of spaced side rail members for supporting said work holding jaws for longitudinal movement therealong, a cross head connecting one end of said side rail members and having a screw rotatable therein connected with one of said work holding jaws for moving said work holding jaw upon rotation of said screw, a plurality of spaced slots on the proximate faces 50 of said side rail members, said slots having paral-

lel proximate faces inclined at an angle to a plane containing said side rail members, a single parallelogram shaped swivelable plate member mounted on the other of said work holding jaws and having planar parallel surfaces on the extremities thereof inclined to the major axis of said single parallelogram shaped swivelable member for locking in said slots, the inclined faces of said spaced parallel slots of said side rail members and said planar parallel surfaces on the extremities of said parallelogram shaped swivelable plate member being adapted for contact upon rotation of said parallelogram shaped swivelable plate member to form a stop against further unintended rotative movement of said parallelogram shaped swivelable plate member and whereby said other work holding jaw may be rapidly adjusted in position on said side rail members and locked in position by said single parallelogram shaped swivelable plate member.

JOHN M. FROBLOM.
